UNITED STATES PATENT OFFICE

103,745

DESIGN FOR A VENETIAN BLIND

John E. Speirs, Brooklyn, N. Y., assignor to Century Venetian Blind Co. Inc., New York, N. Y., a corporation of New York

Application April 15, 1936, Serial No. 62,134

Term of patent 14 years

To all whom it may concern:

Be it known that I, John E. Speirs, a citizen of the United States and a resident of Brooklyn, New York, in the county of Kings and State of New York, have invented a new, original, and ornamental Design for Venetian Blinds, of which the following is a specification, reference being had to the accompanying drawings forming a part thereof, in which

Fig. 1 is a front elevational view, fragmentary in character, of the lower left-hand corner of a Venetian blind in open position, showing the lower rail having a plurality of flutes of approximately the same width as the slats;

Fig. 2 is a view similar to Fig. 1 showing the lower part of the Venetian blind raised sufficiently

so that some of the slats rest on the lower rail, and illustrating the appearance of the rail as harmonizing with a plurality of slats;

Fig. 3 is a fragmentary, cross-sectional view of a rail of the Venetian blind; showing the nature of the flutes, Fig. 4 is a front elevational view of the Venetian blind; and Fig. 5 is an edge view thereof.

The dominant feature of my design consists in a plurality of longitudinal flutes on a rail of approximately the same width as the slats of the Venetian blind.

I claim:—

The ornamental design for a Venetian blind as shown and described.

JOHN E. SPEIRS.
